UNITED STATES PATENT OFFICE.

WILLIAM D. C. PATTYSON, OF MARLBOROUGH, MASSACHUSETTS, ASSIGNOR
OF TWO-THIRDS TO HORACE S. CROWELL AND EDMUND E. BOND, BOTH
OF SAME PLACE.

RAILWAY-TELEGRAPH.

SPECIFICATION forming part of Letters Patent No. 290,602, dated December 18, 1883.

Application filed January 22, 1883. (No model.)

To all whom it may concern:

Be it known that I, WILLIAM D. C. PATTYSON, of Marlborough, county of Middlesex, State of Massachusetts, have invented an 5 Improvement in Railway-Telegraphs, of which the following description, in connection with the accompanying drawings, is a specification, like letters on the drawings representing like parts.

10 My invention has for its object to establish electrical connection between a moving train and a stationary electrical conductor, it being shown in connection with a telegraphic instrument for communicating between the train and stations, or between different trains.

15 The invention is intended as an improvement in the class of apparatus in which a single line-wire is employed, and means are provided for breaking the said line and interposing 20 the train with the apparatus carried by it within the said line.

25 In carrying out this invention the train is provided with long contact-plates or electrodes, preferably carried by the locomotive and tender, co-operating with the electric conductor or line mounted on posts at the side of the track, like an ordinary telegraph-wire. The said wire is provided with circuit-breakers at a 30 distance apart not greater than the length of the contact-plates carried by the train, the said circuit-breakers co-operating with the contact-plates as the train passes in such a manner as to open the main line and connect the portion on each side of the break with one 35 of the contact-plates, so that an instrument placed in the circuit between the contact-plates will be interposed in the main-line circuit as the trains travel along from one circuit-breaker to another, and continuous 40 electrical connection is thus established between the moving train and stations along the main line, or between two moving trains.

45 The invention consists, partly, in the arrangement of the circuits and construction of the receiving-instrument employed for telegraphic communication, the said instrument being adapted to operate when the moving strips are connected with the main line at one or two of the circuit-breakers. The line is preferably provided with resistance-coils, connected 50 with it at either side of the circuit-break-

ers, so that in case one of the circuit-breakers should not close properly after the train has passed the line would not be left open. The said resistance is sufficient to cause the portion of the current traversing the instrument in the train to operate it. The train is preferably provided with two sets of contact-strips, one on each side, and the set that is not in use in connection with the main line 55 is utilized for especial signals or instruments controlled by local circuits at various points, as desired.

60 The invention also consists in the novel construction of the different devices, by which greater certainty of action is insured and the cost of the apparatus reduced.

65 Figure 1 is a side elevation of a locomotive provided with contact-strips co-operating with a main-line wire in accordance with this 70 invention; Fig. 2, a front elevation thereof; Figs. 3 and 4, a plan view and rear elevation, respectively, of one of the circuit-breakers by which the said strips are interposed in the main-line circuit; Fig. 5, a front elevation of 75 a telegraphic receiving-instrument adapted to be used on the train; Fig. 6, a detail showing a connection between the different portions of the moving strip that are carried by different vehicles, and Fig. 7 a diagram of the electric 80 circuits and instruments therein.

85 The train is provided with contact-strips a b a' b' , (shown as mounted on the locomotive and tender,) the said strips being made continuous, as shown in Fig. 6, by a spring, a^2 , connected with the portion of the strip that is carried by one member of the train, and having its end bear on the portion of the strip carried by another member of the train, the said strips being herein shown as extending 90 only the length of the locomotive and tender. A steam-pipe, a^3 , may be run along adjacent to the strips, to prevent the formation of ice thereon.

95 The main electric circuit or line consists of an ordinary telegraph-wire mounted on posts c at the side of the track, the said posts being at a distance apart somewhat less than the length of the strips a b , so that one of the posts will always be opposite some portion of the 100 said strips. The main line is provided at each post with a circuit-breaker, shown in Figs. 3

and 4 as consisting of a metallic arm or plate, *d*, fixed on the post, and contact-springs *e e'*, connected with the line-wire at each side of the post, and normally pressed against the 5 plate *d* by spring-fingers *f f'*, carried by an arm, *f²*, pivoted upon the said post, and provided at its end with metal contact-pieces *h i*, arranged to rub against the strips *a b*, respectively, as the train passes by, the said train at 10 the same time turning the arm *f²* on its pivot, as shown in dotted lines, Fig. 3. The line coming to the post *c* on one side and connected with the spring *e* is also connected with one of the contact points, as *i*, at the end of the arm *f²*, 15 while the line leaving the post on the other side and connected with the spring *e'* is also connected with the contact-point *h* at the end of the arm, and the arm *f²* is provided with projections *f³*, which, when the arm *f²* is 20 swung on its pivot by the passing train, engage one of the spring-fingers *f* or *f'*, and remove it from the corresponding spring, *e* or *e'*, which is then disconnected by its elasticity from the plate *d*, breaking the direct connection between 25 the portions of the line at either side of the post. When the train is not passing, the arm *f²* stands in its normal position at right angles to the track, as shown in full lines, Fig. 3, it being held in this position by the spring-fingers *f f'*, which are connected with its pivot or shaft. (See Fig. 3.) The said springs *e e'* are 30 in electric contact with the plate *d*, and the circuit is continued directly from the line on one side of the post to the line on the other side. The line coming toward and leaving the post *c* is preferably also connected with 35 resistance-coils *m*, so that when a proper contact is not afforded between the parts *d e e'* a circuit will still be maintained through the said resistance-coils *m*, which will be of considerable amount relative to the resistance of the instruments that are to be connected in circuit between the plates *a b*. The fingers *f f'* are shown as insulated where they engage the 40 45 springs *e e'*.

The contact-piece *h* may be provided with a roller to reduce its friction on the strip *a*, and the contact-piece *i* is made somewhat flexible, it being shown as a metallic brush, which 50 may be adjustable on the arm *f²*.

If it were possible to space the circuit-breakers with such accuracy that the plates *a b* would always make contact with one at the precise moment that they left the preceding one, it will be seen that an ordinary relay or 55 sounder could be placed in circuit between the plates *a* and *b*, and operated by opening and closing the line, or in any usual manner. In order, however, to insure the continuity of 60 the circuit through the train, the circuit-breakers are so arranged that the strips will come in contact with each one just before they have left the preceding one, and the strips will, consequently, for short spaces of time, be in contact with two circuit-closers. In order to 65 insure the proper operation, whether the strips are in contact with one or two circuit-closers,

one of the said strips is divided transversely, as shown at 2, and the instrument has two separate portions, one in circuit between one portion of the divided strip and the other strip, and the other portion of the instrument in circuit between the other portion of the divided strip and the undivided strip. The two portions of the instrument are shown in Fig. 5 as 70 electro-magnets *n o*, having their cores mounted in line with one another on a single back-strap, and acting on a single armature, so that if either of the said magnets is charged the armature will be attracted. One of said magnets, as *n*, is connected in circuit between one portion of the said strip *a* and the strip *b*, as shown, by the wires 3 4 5, and the other magnet, *o*, is connected in circuit between the other portion of the strip *a* and the strip *b* by wires 75 7, 8, and 5.

In the diagram Fig. 7 the strips are shown as connected with two of the circuit-breakers, so that the direct main line is broken between 20 and 23, as well as between 23 and 26. The 90 main line 20 is connected by wire 21 with the contact-piece *h*, and the contact-brush *i* is connected by wire 22 with the piece *e'* and line 23, which is connected with the spring *e*, and by wire 24 with the contact-piece *h* of the 95 next circuit-breaker, the contact-piece *i* of which is connected by wire 25 with the spring *e'*, which is also connected with the main line 26, beyond the circuit-breakers acted upon by the strips *a b*.

As shown, the main line is provided with opposing batteries *B B'* at its ends, so that by grounding it at any point the currents of both batteries will pass through the stations between them and the said grounded point; or, 105 by removing one battery, signals may be transmitted in the usual way by opening and closing the line.

The circuit through the magnets *n o* of the receiving-instrument may be traced as follows: 110 From the battery *B* it passes by wires 20 21 to the contact-piece *h* and strip *a*, from which the circuit is continued by wire 3 to the magnet *n*, and thence by wire 5 to the strip *b*, contact-piece *i*, and wires 22 and 23 to the other end 115 of the line, except at the moment when, as shown in the drawings, the next circuit-breaker, *d e'*, is also open. In such case the circuit is continued from the strip *b* to the wires 25 and 26, the wires 22 23 being then cut out. 120 When in the movement of the train in the direction of the arrow the strips *a b* pass off from the contact-points *h i*, connected with wires 21 23, the circuit will be closed at *d e'*, connecting the wire 20 directly with the wire 23, and the circuit will then be from wire 23 through wire 24, strip *a*, wire 7, magnet *o*, wires 8 and 5, strip *b*, contact-piece *i*, and wires 25 and 26, the circuit then including only the magnet *o*, until after the severed point 2 of the strip 125 passes the contact-points *h i*, when the circuit will be only through the magnet *n*, as follows: 130 24 a 3 n 4 n 5 b i 25 26. The instrument *n o* will thus be kept interposed in the main-line

circuit, and will receive signals transmitted over the line in any usual manner.

In order to transmit signals from the train the main line 20 26 may be connected with the 5 wheels and axles, and thus with the rails which form the ground or return circuit of the main line. The wire 5 is shown as connected by wire 12 with the usual key, K, and switch S, the anvil-piece of which is connected by wire 13 with the wheels and rails. The main line 20 26 may thus be grounded by the key and switch in the usual manner, forming independent circuits for the batteries B B', so that signals will be transmitted through any other 15 train that may be interposed in the circuit, as well as through the fixed stations.

It will be seen that if the resistance-coils m are not used there would be an undivided circuit through the instrument, and the signals 20 might be transmitted by opening and closing the circuit in the usual manner.

It is obvious that the magnets n o and their armature might constitute any usual kind of receiving-instrument, either a relay to open 25 and close a local circuit or a sounder; or, if desired, the armature might constitute the diaphragm of a telephonic instrument; or any other form of electric apparatus might be included in the circuit between the strips a b.

30 In order to operate especial signals on the approach of a train, as at stations or highway-crossings, the posts c and arms f² may be provided with an additional circuit-closer, p, shown in Fig. 3 as consisting of a spring connected with the post and a stud connected with the arm, and brought in contact with the said spring when the arm is swung on its pivot by the train. One portion of the said circuit-closer may be connected directly with the rail 35 or ground, while the other is connected with a wire passing through the battery and signaling-instrument at any desired point. It will be seen that the said circuit-closers p will be closed only when the arms f² are turned in one direction, so that for single-track roads they 40 may be arranged to operate a signal when the train is approaching a given point, but not after it has reached and is receding from the said point, the said arm f², however, being arranged to break the main circuit at d e or e' 45 and connect its ends with the strips a b by the movements of the said arms on their pivots in either direction.

For convenience in operation, the trains will 50 be provided with contact-strips on each side, as best shown in Fig. 2, and while the strips on the one side will be interposed in the main-line circuit, as previously described, those on the other side may be employed for operating 55 special signals in the train. For instance, as shown in Fig. 7, one portion of the strip a' is connected by wire 30 with a signal of any usual character—such, for example, as an automatic vibrating bell, r, on the locomotive—the other 60 terminal of which is connected by wire 31 with the wheels and axles or ground.

The contact-piece i', co-operating with strip

a', may be connected by wire 32 with a circuit-closer, t, which may, for instance, be operated by the movable rails of a railway-switch, or in 70 any other way, when it is desired to signal a train to stop, the said circuit-closer being shown as connected through the battery B² with the ground, so that in case the circuit-closer t is closed a current will be transmitted 75 through the signal r as soon as the train arrives at the contact-piece i', which may be mounted on an arm pivoted on a post precisely like those previously described.

The strip b' is shown as connected by wire 80 40 with a series of magnets, u, controlling the detents of station-indicators of suitable construction, from which the circuit is continued by the wire 41 to the ground. The contact-piece h', co-operating with the said strip b', may 85 be connected by wire 42 with a local battery, as B², at each station, so that when the train approaching or leaving the station arrives at the contact-piece h', an impulse will be transmitted 90 through the said magnets u, operating the station-indicator.

The invention is not limited to the specific form of circuit-breakers employed in the main line for interposing the train and the connected 95 instruments in the circuit.

It will be seen that by separating a line from point to point as a train travels by it, as herein described, and interposing the train or apparatus carrier thereby in the opening thus produced, a train may be maintained 100 continuously in circuit with the employment of but a single stationary conductor.

When the apparatus is to be employed in connection with a road having several parallel tracks, the arms f² may be pivoted to swing 105 in a vertical plane upon beams extending across the entire series of tracks.

The arms of the circuit-breakers may be adjusted to the proper position relative to the track by gaging-strips carried by a hand-car 110 or other construction-car, and the strips a b a' b' may be adjustably connected with the locomotive or train. Any suitable form of electric connections can be used between the different rails of the track, which will form a 115 sufficiently perfect conductor of electricity.

The magnets—such as u—might be employed to operate an alarm upon freight-trains, for 120 warning a brakeman, as they approach a bridge.

125 Posts carrying wipers may be employed from point to point to clear the contact-strips of snow or other matter which may be deposited upon them, such wipers preferably being placed at each side of a railway-station. The mechanism at the tops of the posts will be protected by any suitable cap or cover.

The receiving-instrument will usually be placed in a special operator's room, which may be padded or provided with means for deadening sound as much as possible.

I have herein shown and described, in addition to the apparatus employed for communication between the different trains or between

trains and stations, additional devices for utilizing a portion of the said apparatus for other special purposes when it is not employed for such communication; but I do not herein claim these devices, as they will form the subject of other applications for Letters Patent.

I claim—

1. The combination of the contact-strips carried by a train with the main line and series of pivoted circuit-breaking arms, having contact-points co-operating with the said strips and connected with the portions of the main line at either side of the said arm, and a circuit-breaking device between the said portions of the main line operated by the movement of the said arm on its pivot, substantially as and for the purpose set forth.

2. The main line and circuit-breakers therein and contact-pieces connected with the said line at either side of the said circuit-breakers, combined with the contact-strips co-operating with the contact-pieces, and the receiving instruments having two portions, one of the said strips being separated into two parts and the portions of the receiving-instrument being in circuit between the said parts of the divided strip, respectively, and the other strip, substantially as described.

3. The pivoted arm adapted to be engaged and turned on its pivot by a passing train, combined with contact pieces or springs con-

nected with the portions of the main line at each side of the said arm, and spring-fingers mounted on the said arm, co-operating with the said contact-pieces, as described, whereby the said arm is normally retained substantially at right angles to the track, and the said contact-pieces in electrical connection, but the latter are electrically separated when the said arm is turned on its pivot in either direction, substantially as described.

4. The main line and circuit-breakers therein, operated by the passing trains to interpose apparatus carried by the train in the said line, combined with resistance-coils connected with the said line on either side of the circuit-breakers, substantially as and for the purpose described.

5. The main line and circuit-breakers therein, operated by the passing trains to interpose apparatus carried by the train in the said line, combined with means for grounding the said circuit upon the moving train, substantially as described.

In testimony whereof I have signed my name to this specification in the presence of two subscribing witnesses.

WM. D. C. PATTYSON.
